UNITED STATES PATENT OFFICE.

FRANK W. DRISH, OF SULLIVAN, ILLINOIS.

CRUMB TRAY.

1,407,053.

Specification of Letters Patent. Patented Feb. 21, 1922.

Application filed June 7, 1921. Serial No. 475,766.

To all whom it may concern:

Be it known that I, FRANK W. DRISH, a citizen of the United States, and a resident of Sullivan, in the county of Moultrie and 5 State of Illinois, have invented new and useful Improvements in a Crumb Tray, of which the following is a specification.

My invention relates to crumb trays and its object is to improve and generally 10 simplify the construction set forth in my pending application for crumb trays filed August 17, 1920, Serial No. 404,048.

A more specific object of the invention is to provide a crumb tray including a revolvable brush or sweeper mounted at the forward edge of the tray and a removable top 15 for the tray together with novel locking means for retaining these parts assembled and which is such as to readily permit the 20 tray to be disassembled for cleaning or other purposes.

With the preceding and other objects and advantages that may become apparent from the following disclosure, the invention consists in the novel combination of contents, 25 constructions and arrangements of parts to be hereinafter specified, claimed and illustrated in the accompanying drawing, wherein—

30 Figure 1 is a perspective of the crumb tray, parts being broken away,

Fig. 2 is a top plan view of the tray having parts of the top thereof shown in horizontal cross section,

35 Fig. 3 is a view partly in cross section and partly in elevation of the device, and

Fig. 4 is a fragmentary perspective of the several parts of the tray disassembled.

Referring in detail to the drawing, where- 40 in similar characters of reference designate corresponding parts throughout the several views, the numeral 5 designates a tray or scoop from one side of which a handle 6 ex- tends. This tray or scoop is formed with, 45 at its opposite ends and at the forward edge thereof, a pair of arms 7 provided with vertically disposed longitudinally aligned slots 8 open at their upper ends. A revolvable brush is indicated at 9 and is disposed forwardly 50 of the tray 5 between the arms 7 and has its shaft 10 journaled in the slots 8.

Removably mounted upon the tray 5 is a top 11 provided with a downwardly extending marginal flange 12 at its forward edge 55 which is disposed forwardly of the revo-

luble brush 9 and constitutes a forward wall for the tray to prevent any crumbs that may adhere to the brush from being carried from the tray during the rotation of the brush over the surface to be swept or crumbed. 60 The flange 12 at its opposite ends is provided with rearwardly disposed extensions 13 which overlie the arms 7. These extensions 13 are provided with open ended slots 14 that extend at right-angles to the slots 8 65 and receive the projecting ends of the shaft 10 and thereby hold the brush against vertical movement.

In order to lock the top wall in position there is provided disks 15 each of which is 70 provided with a slot 16. Projecting laterally from each of the extensions 13 is a pin 16'. The disks 15 are provided with arcuate slots 17 in which the pins 16 are engaged to pivotally connect these disks to the extensions 13. As is shown in Fig. 1, the locking disks 15 are normally positioned with their slots 16 extending vertically. However, when it is desired to disassemble the tray 75 these disks are rotated to dispose their slots 80 in parallelism with the slots 14. It will be obvious with the disks in this position the top wall 11 may be slid forwardly to disengage the extensions 13 from the shaft 10 and that the brush 9 may then be raised vertically from the arms 7.

It is to be understood that the form of my invention herein shown and described is to be taken as a preferred example of the same, and that various changes in the shape, size 90 and arrangement of parts may be resorted to without departing from the spirit of the invention or the scope of the subjoined claims.

Having thus described my invention, what I claim as new and desire to secure and protect by Letters Patent of the United States 95 is:

1. A crumb tray including a tray having forwardly extending arms provided with vertical slots open at their upper ends, a rotatable brush having its ends journaled in the slots, a top wall removably positioned on the tray, a downwardly extending flange extending from the forward edge of the top of the wall and disposed forwardly of the brush, rearwardly disposed extensions carried by the flange and provided with horizontally disposed slots which receive the ends of the brush, and pivoted locking ele- 100 ments carried by the extensions and engag- 105 e 110

ing the ends of the brush to hold the latter against lateral movement.

2. A crumb tray including a tray having forwardly extending arms provided with 5 vertical slots open at their upper ends, a rotatable brush having its ends journaled in the slots, a top wall removably positioned on the tray, a downwardly extending flange extending from the forward edge of the top of 10 the wall and disposed forwardly of the brush, rearwardly disposed extensions car-

ried by the flange and provided with horizontally disposed slots which receive the ends of the brush, and locking disks pivotally mounted on the extensions and provided with slots receiving the projecting ends of 15 the brush, the locking disks being adapted to be swung to a position to dispose their slots in parallelism with the slots in the extensions in order to permit the top wall to be 20 removed from the tray.

FRANK W. DRISH.
